REFRIGERATION

Clyde E. Ploeger, Evansville, Ind., assignor to
 Servel, Inc., New York, N. Y., a corporation of
 Delaware

Application December 20, 1935, Serial No. 55,309

4 Claims. (Cl. 62—4)

My invention relates to refrigeration and more particularly to a system of refrigeration in which air is caused to flow or circulate in thermal exchange relation with a cooling element of a refrigeration apparatus by means of a fan or other device for producing a forced draft.

It has been proposed to cool air in a refrigerator by circulating the air over an evaporator of a compression type refrigeration apparatus by means of a fan or blower, the fan operation being controlled responsive to temperature of the air, and the refrigeration apparatus being suitably controlled so that operation periods of the refrigeration apparatus are instigated a time interval after instigation of the corresponding operating periods of the fan. With this type of control, operation of the fan while the refrigeration unit is idle causes defrosting of the cooling element and as a consequence there is maintained a higher humidity of the air.

It is an object of my invention to provide a system of this character in which operation of a refrigeration apparatus is instigated a predetermined time interval after operation of a fan is instigated, whereby, by alteration of the time interval, there is obtained control of the humidity.

My invention will be more fully understood upon reference to the following description and accompanying drawings forming part of this specification and of which:

Fig. 1 illustrates diagrammatically a forced draft refrigeration system embodying the invention; and

Figs. 2 and 3 are similar to Fig. 1 and illustrate other operative conditions of the system.

Referring to Fig. 1, an enclosure 10 to be refrigerated is indicated in dotted outline. In the enclosure 10 is a cooling element comprising an evaporator coil 11 of a compression type refrigeration apparatus. The other parts of this apparatus include a condenser 12 and a compressor 13 driven by an electric motor 14. Refrigerant liquid evaporates in the cooling coil 11, producing a refrigerating effect. The resulting vapor flows through conduit 15 to the compressor 13 in which the refrigerant vapor is compressed and discharged through a conduit 16 to the condenser 12. In the latter, the refrigerant vapor is liquefied and the liquid flows through conduit 17 to the coil 11, thus completing the refrigeration cycle. Flow of liquid from the high pressure condenser to the low pressure evaporator coil 11 is controlled by any suitable device such as a

thermostatically operated expansion valve 18 in the conduit 17.

An electric fan or blower 19 is arranged in the enclosure 10 to cause circulation of air in contact with the evaporator coil 11. There is also provided in the enclosure 10 a thermostatic switch 20 which is subjected to temperature of the air in the refrigerator enclosure.

The compressor motor 14 and the electric fan 19 are connected in a manner hereinafter described to a source of electric current supplied by what will be termed line conductors 39 and 42.

It is desired to maintain the air in the refrigerator enclosure 10 at a certain temperature, that is, within certain temperature limits. Assuming that the temperature in the enclosure is above the desired limit, we want to operate the refrigeration apparatus to maintain the evaporator 11 at a low temperature and operate the fan 19 to blow air over the evaporator 11 until the temperature of the air in the enclosure is brought down to the desired value. We then wish to discontinue operation of the refrigeration apparatus and fan until again required. These alternate periods will be referred to as operation periods and idle periods. During operation periods, water vapor is condensed out of the circulating air and deposited on the evaporator coil 11 where it may freeze and form frost. The absolute humidity of the air is thereby reduced.

If we operate the fan to blow air over the coil 11 while the condensing unit is idle, the resulting flow of relatively warm air will cause the frost to melt and the water evaporate into the air, thus increasing the humidity of the air. If this is accomplished each cycle of operation, the humidity of the air will not be continually decreased as it would be if the frost were allowed to build up cycle upon cycle.

To accomplish the above results I provide a control circuit for the condensing unit motor 14 and the electric fan 19 whereby these motors are started and stopped responsive to temperature of air in the enclosure 10 and the electric fan 19 starts a predetermined time interval ahead of the condensing unit motor 14. In addition to the motors 14 and 19, this control circuit includes the previously mentioned thermostatic switch 20, a transformer 21, a first solenoid operated switch 22, a second solenoid operated switch 23, and a timing device 24. I will now describe these elements individually.

The thermostatic switch 20 may be of any suitable type which closes upon rise in temperature and opens upon decrease in temperature. This

switch is preferably snap-acting so as to definitely open and close between temperature limits for which it is adjusted. The first solenoid operated switch 22 comprises an operating coil 25 and a pair of normally open contacts 26. The second solenoid operated switch 23 comprises an operating coil 21, two sets of normally open contacts 28 and 29, and a set of normally closed contacts 30. The transformer 21 has a desired voltage ratio for stepping the line voltage, for instance, 110 volts, down to a desired secondary voltage such as, for instance, 24 volts.

The timing device 24 is operated by a suitable electric motor 31 which may be a self-starting synchronous motor. The timing device includes a first switch having an adjustable contact 32 and a rotatable contact 33. The contact 32 may be adjusted by turning a knob 34. There is also a normally closed switch 35 operated by a rotatable arm 36. The rotatable switch contact 33 and the switch operating arm 36 are arranged to be driven by the timer motor 31 through suitable speed reducing gearing 37.

One terminal of the condensing unit motor 14 is connected by means of a conductor 38 to one side of the supply line 39, and the other terminal of the motor 14 is connected by a conductor 40, a normally open contact 29 of switch 23, and conductor 41 to the other side 42 of the supply line.

One terminal of the fan motor 19 is connected by means of a conductor 43 to one side 39 of the supply line and the other terminal of the fan motor is connected by means of a conductor 44, the normally open contact 26 of switch 22, and a conductor 45 to the other side 42 of the supply line.

From the above described connections it will be understood that operation of the fan 19 is instigated on operation of switch 22, and operation of the condensing unit motor 14 is instigated on operation of switch 23. The switch operating coils 25 and 27 are energized from a circuit including the secondary of the transformer 21 which is connected between the supply line conductors 39 and 42, and this circuit is controlled by the thermostatic switch 20 and the timing device 24.

One side of the secondary of the transformer 21 is connected by means of a conductor 36 to one contact of the thermostatic switch 20. The other contact of this switch is connected by means of a conductor 47 to one end of each of the switch operating coils 25 and 27. The other end of the switch operating coil 25 is connected by means of a conductor 48 and a conductor 49 to the other side of the secondary of the transformer 21. It will now be understood that the switch operating coil 25 is energized when the thermostatic switch 20 is closed. The other end of the switch operating coil 27 is also connected to the other side of the secondary of the transformer 21 by means of a conductor 59, a normally open contact 28 of the switch 23, a conductor 50, and the conductors 48 and 49. It will now be understood that the switch coil 27 will not be energized upon closing of the thermostatic switch 20 until its circuit is closed by some other means.

This other means is the switch contacts 32 and 33 of the timing device 24. The contact 32 is connected by means of a conductor 51 and the conductor 49 to the secondary of the transformer 21. The contact 33 is connected by means of a conductor 52 to the switch operating coil 27. It will now be understood that the operating coil 27 will be energized when the timer contacts 32

and 33 are closed. Since operation of the timer 24 is instigated upon closing of the thermostatic switch 20, as hereinafter described, the timer contact 32 may be rotated by means of the knob 34 to a desired position so that it is not contacted by the rotatable contact 33 until after a time interval of operation of the timing device. Therefore, the solenoid switch 23 does not operate until this predetermined time interval after operation of the solenoid switch 22 which operates immediately upon closing of the thermostatic switch 20.

One terminal of the timer motor 31 is connected by means of a conductor 53 to one side of the supply line 39. The other terminal of the timer motor 31 is adapted to be connected to the other side 42 of the supply line by way of two parallel paths. One path includes a conductor 54, the normally closed contact 30 of switch 23, a conductor 55, a conductor 56, the normally open contact 26 of the switch 22, and the conductor 45. The other path includes a conductor 57, the limit switch 35 of the timer 24, a conductor 58, conductor 56, contact 26 of the switch 22, and conductor 45. It will now be understood that the timer motor 31 can operate only when the switch contacts 26 are closed, that is, when switch 22 is operated, and this occurs upon closing of the thermostatic switch 20. It will also be understood that operation of the timer motor 31 ceases, even though the switch contact 26 be closed, when the switch contacts 30 and 35 are both open.

I will now describe the complete cycle of operation. Assuming that the temperature of the air in the refrigerator enclosure 10 is within the desired limits, the thermostatic switch 20 is open, no parts are in operation, and the timer 24 is in its initial or normal position. These conditions are illustrated in Fig. 1. This is an idle period. Due to flow of heat into the refrigerator enclosure 10, the temperature of the air increases in this enclosure until it reaches the predetermined upper limit. Thereupon, the thermostatic switch 20 closes to energize coil 25 of the switch 22. Operation of switch 22, that is, closing of contact 26, initiates operation of the electric fan 19. Circulation of air over the refrigerator coil 11 produced by operation of the fan 19 causes any frost or condensed moisture which may have been formed on the coil 11 to evaporate into the air stream, thus increasing the humidity of the air. Operation of the switch 22 also instigates operation of the timer 24. Thereupon, contact 33 starts to move toward contact 32, and the switch arm 36 releases the contacts 35 to their closed position. In Fig. 2, the thermostatic switch 20 has closed, the first solenoid switch 22 has operated, the fan 19 is causing circulation of air in the enclosure 10, and the timer 24 has started to operate.

After a predetermined time interval of operation of the timer 24, depending upon the setting of the contact 32, the rotatable contact 33 closes upon the contact 32, completing the circuit of the second solenoid operated switch 23. Operation of the switch 23 instigates operation of the condensing unit motor 14 by closure of contacts 29. This is illustrated in Fig. 3 which shows the contacts 32 and 33 closed and the switch 23 operating. Operation of the condensing unit motor places the refrigeration apparatus in operation to cool the air being circulated by the fan 19.

At the same time opening of the contacts 30 of the switch 23 places control of the timer

motor circuit upon the limit switch 35 of the timer 24. Also, closing the holding contacts 28 of the switch 23 bridges in a parallel circuit the timer contacts 32 and 33 so that the latter may now open and the switch 23 remain energized. The timer 24 continues to operate until the arm 36 has made a complete revolution and returns to its position shown in Fig. 1, whereupon the switch 35 opens the circuit of the timer motor 31 and the timer again becomes inactive. The switches 22 and 23 remain closed, continuing operation of the refrigeration apparatus and the fan, until the temperature of the air in the refrigerator enclosure 10 is decreased to the lower desired limit, whereupon the thermostatic switch 20 opens the energizing circuit of the switches 22 and 23 which open and thereby terminate the operation periods of the refrigeration apparatus and the fan. The control circuit is again in the condition illustrated in Fig. 1.

It will be understood that various changes and modifications may be made within the scope of the invention as indicated by the following claims.

25 What I claim is:

1. Air cooling apparatus including an evaporator for absorbing heat from air to be cooled, a compressor, a condenser, said compressor, condenser and evaporator being operatively connected to form a refrigeration system, a motor for driving the compressor, a fan for directing air to be cooled in thermal contact with said evaporator, a motor for driving said fan, and means responsive to temperature of the air to be cooled for controlling operation of said motors and including adjustable means for delaying starting of said compressor motor a predetermined time interval after starting of said fan motor.

40 2. An air cooling system including refrigeration apparatus having a cooling element and op-

erated by an electric motor, a blower operated by an electric motor for circulating air in thermal contact with said cooling element, a first switch for controlling operation of said blower motor, a second switch for controlling operation of said refrigeration apparatus motor, means for operating said switches responsive to temperature of the air to be cooled, and adjustable means for delaying closing of said second switch a predetermined time interval after closing of 10 said first switch.

3. Air cooling apparatus including an evaporator, a condenser, a compressor driven by an electric motor, a blower operated by an electric motor for circulating air in thermal contact with 15 said evaporator, a first solenoid operated switch for controlling said blower motor, a second solenoid operated switch for controlling said compressor motor, an adjustable delayed closing switch for controlling said second solenoid operated switch, and a thermostatic switch responsive to temperature of air to be cooled for controlling energization of said first solenoid switch and said time delay switch and de-energization of both of said solenoid operated switches. 20

4. In a method of cooling air which includes causing circulation of air to be cooled in thermal contact with a cooling element operating at a temperature such that frost may be formed thereon by condensation and freezing of water vapor 30 in the air, that improvement which consists in intermittently circulating cooling fluid through said cooling element and intermittently causing circulation of the air to be cooled, both responsive to temperature of the air to be cooled, 35 and instigating circulation of the air different time intervals prior to instigation of circulation of the cooling fluid to melt and evaporate into the air frost which may have been formed and thus maintain different humidity conditions. 40
